(57) **CLAIM**

The ornamental design for a front sight as shown and described.

DESCRIPTION

FIG. 1 is an isometric view of a front sight, showing my new design;

FIG. 2 is a rear isometric view thereof;

FIG. 3 is a left side view thereof;

FIG. 4 is top view thereof;

FIG. 5 is a right side view thereof;

FIG. 6 is a front view thereof;

FIG. 7 is a rear view thereof;

FIG. 8 is an isometric view of another front sight, showing my new design;

FIG. 9 is a rear isometric view thereof;

FIG. 10 is a left side view thereof;

FIG. 11 is top view thereof;

FIG. 12 is a right side view thereof;

FIG. 13 is a front view thereof;

FIG. 14 is a rear view thereof;

FIG. 15 is an isometric view of yet another front sight, showing my new design;

FIG. 16 is a rear isometric view thereof;

FIG. 17 is a left side view thereof;

FIG. 18 is top view thereof;

FIG. 19 is a right side view thereof;

FIG. 20 is a front view thereof;

FIG. 21 is a rear view thereof;

FIG. 22 is an isometric view of yet another front sight, showing my new design;

FIG. 23 is a rear isometric view thereof;

FIG. 24 is a left side view thereof;

FIG. 25 is top view thereof;

FIG. 26 is a right side view thereof;

FIG. 27 is a front view thereof;

FIG. 28 is a rear view thereof;

FIG. 29 is an isometric view of yet another front sight, showing my new design;

FIG. 30 is a rear isometric view thereof;

FIG. 31 is a left side view thereof;

FIG. 32 is top view thereof;

FIG. 33 is a right side view thereof;

FIG. 34 is a front view thereof; and,

FIG. 35 is a rear view thereof.

The dot-dash broken line represents a break line or, when adjacent to the claimed design, represents an unclaimed boundary of the claimed design. The broken lines depicting the remainder of the front sight show features that form no part of the claimed design.

1 Claim, 15 Drawing Sheets
